CALIFORNIA.

DAM.

1,081,199.

Specification of Letters Patent.

Patented Dec. 9, 1913.

Application filed July 12, 1909, Serial No. 507,246. Renewed May 6, 1913. Serial No. 765,908.

To all whom it may concern:

Be it known that I, GEORGE SYDNEY BINCKLEY, a citizen of the United States, residing at Oceanpark, in the county of 5 Los Angeles and State of California, have invented new and useful Improvements in Dams, of which the following is a specification.

This invention relates to dams for stoppage, diversion and impounding of streams and bodies of water; and it has for its object to provide an improved dam which will be superior in point of durability, positiveness and security in service, relative simplicity and inexpensiveness of construction and installation, and general efficiency.

Dams as now constructed according to standard practice are designed to obtain the required opposition to the pressure of the 10 impounded water, with consideration particularly to massiveness or great transverse dimensions. The holding function is ordinarily predicated upon the disposition in the normal course of the otherwise unobstructed 15 water of sufficient masonry, or other material, to withstand the water pressure through the gravity of the mass. In designing dams along these lines, attention has generally been paid to sectional formation, 20 with the object in view of providing sufficient weight in the structure itself to resist the overturning tendency of the water obstructed or impounded. But it has remained for further calculation and utilization of 25 physical principles to devise a dam with relatively increased maximum of holding efficiency and relatively decreased minimum of mass, with the resultant relative decrease of cost of material and labor entering into 30 construction and installation.

With the latter objects in view, I have devised a dam resting upon the principle of a cone or conoid for its high efficiency of holding function or capability of resistance 45 to water pressure. The adaptation of the cone or conoid principle to dam construction, resulting in the production of a dam the profile and sections of which pertain to the cone or conoid, enables the provision of a 50 dam of increased holding capability and decreased cost, both with relation to present standard practice.

The invention consists in the novel utilization of the principle of the cone or conoid in 55 dam construction, and embodied in the pro-

vision, formation, construction and combination of parts and features all as hereinafter described, shown in the drawing and finally pointed out in claim.

In the drawing: Figure 1 is a detail vertical sectional view, taken upon the line 1—1, Fig. 2, and looking in the direction of the appended arrows, of a dam constructed according to the invention; a portion of a body of water being illustrated as in contact 60 with the face or profile thereof; Fig. 2 is a top plan view of the dam construction shown in Fig. 1; and, Fig. 3 is a rear elevation of the dam construction shown in the other figures, upon a diminished scale; a portion of 70 the surrounding and sustaining formation being shown in connection therewith.

Corresponding parts in all the figures are designated by the same reference characters.

Referring with particularity to the drawing; A designates the improved dam embodying the invention; the same being installed in position for service in connection with or in physical opposition to a body of water B, which is obstructed by the dam A. 80

C designates a portion of the formation, of the bed and banks of a stream within and in connection with which the dam A is installed.

The dam A, which may be of any construction and formation with respect to its constitution and organization in part or in whole, and the composition of which may be of concrete, masonry, or other material, has the general form of a truncated fragmentary cone or conoid, the crown a of which may be plane, and the base b of which may be formed as desired and requisite for its proper installation in and connection or uniting with the formation C; 90

the extreme base being embedded in such formation. The crown a describes approximately the arc of a circle having its center down-stream or away from the obstructed water B; and the pressure receiving face or profile c of the dam has a curvature corresponding in general to that of the surface of a cone or conoid; whereby an approximately straight line may be drawn upon and lying within the face or profile c, from any point of the crown a, and in a vertical plane, to the base b. The forward face c has an increasing radius from the crown a toward the base b. The rearward face d of the dam may be of any predetermined and desired 100 105 110

formation in conformity with the massing of the constituent material of the dam between the faces *c* and *d*.

In practice it will be found that the transverse dimensions of the dam, that is, the thickness of the same between the faces *c* and *d*, may be so relatively decreased with respect to dams of standard formation, that the formation of the rear face *d* will correspond in general to that of the forward face *c*, the forward face *c* being convex and the rearward face concave. The transverse dimensions of the dam are preferably varied from the crown of the same to the base of the same, increasing in sectional area from the former to the latter, as shown in Fig. 1, and indicated therein by the broad vertical curvature of the rearward face *d*.

With the improved dam installed on a formation *C*, such as shown in the drawing, the profile of which corresponds to a general curved depression beneath the plane of the crown *a* of the dam, such depression being greatest substantially centrally of the dam, the forward face *c*, or the portion thereof directly receiving the pressure of the body of water *B*, will vary in altitude, increasing in altitudinal dimensions toward the vertical center of the dam; or decreasing in such dimension from the vertical center of the dam toward the sides thereof. The base lines of the forward face *c* of the dam, at various altitudinal levels above the extreme depth of the body of water *B*, where the forward face of the dam meets with the formation *C*, are indicated in Fig. 2, between the lines designated by figures of altitude, the same altitudinal figures being given in Fig. 1.

The operation, principle of construction and service, and advantages, of the improved dam constituting the invention, will be readily understood from the foregoing description taken in connection with the accompanying drawing and the following statement:—The dam *A* being of generally conical or conoidal form with respect particularly to the forward face or profile *c*

thereof, the pressure of the body of water *B* upon the upwardly inclined profile *c*, is transmitted to the surrounding and supporting formation *C* through the dam along such lines resultant of horizontal and vertical pressure as to add to the stability and safety of the dam in its opposition to the stress of the body of water *B*. Such resultant is indicated approximately by the arrow in Fig. 1. The pressure of the water upon the dam therefore tends to more firmly anchor and sustain the same in its bed or location in connection with the formation *C*; and its arched form in the horizontal plane gives support to the structure against the pressure of the impounded water, and transmits the horizontal stresses originating in such pressure to the abutments and the formation *C*. It results, therefore, that the dam will hold and stand against the pressure of the body of water in spite of decrease of transverse dimensions of the dam with relation to those of dams of other types; and that whereas such dams of other types under the same pressure and having relatively increased transverse dimensions might fail and be swept away or demolished, the improved conoidal dam constituting the invention will remain stable and safe. It will be understood that the faces *c* and *d* referred to herein as the forward and rearward faces, designate respectively the faces which are presented up-stream and down-stream.

Having thus described my invention, I claim and desire to secure by Letters Patent:—

A dam having a horizontal curvature the radius of each face of which increases downwardly through a portion of the height thereof.

In testimony whereof, I have signed my name to this specification in the presence of two subscribing witnesses.

GEORGE SYDNEY BINCKLEY.
